S. Booth,
Coal Screen.

N° 18,430.

Patented Oct. 20, 1857.

UNITED STATES PATENT OFFICE.

SAMUEL BOOTH, OF NEW YORK, N. Y.

COAL-SIFTER.

Specification of Letters Patent No. 18,430, dated October 20, 1857.

To all whom it may concern:

Be it known that I, SAMUEL BOOTH, of New York, county of New York, and State of New York, have invented certain new and useful Improvements in Coal-Ash Sifters; and I do hereby declare that the following is a full, clear, and exact description of the same, reference being made to the annexed drawing, making a part of this specification, 10 which is a longitudinal vertical section, exhibiting interior and operation—that is to say—

My improvement in coal ash sifters lies in the construction and arrangement within a 15 closed box, intended as a receptacle for coal ashes and cinders, of a screening apparatus, which shall effect the operations of sifting the cinder from said ashes without allowing the dust to escape, and depositing the same 20 in separate compartments by the mere act of emptying said ashes and cinders into the said box.

Heretofore ash sifters have always required some special work or operation to 25 effect the separation of the cinder, which work, as is well known, is reluctantly performed and generally avoided by domestics as much as possible, by reason of the extra labor required, as well as from the 30 disagreeable character of the work by reason of its dirt and dust. It is well known that some kind of force or mechanical action is necessary in order to accomplish such a result; hence the usual employment of 35 means to effect the agitation of the sieve. By the form of construction I have adopted I am enabled to employ, as the required 40 mechanical action, the force of impact, and I avail myself of this by so arranging a screen in connection with a chute-board, that the ashes, &c., will strike upon it perpendicularly or nearly so to its surface, whereby the most of the finer particles will at once pass through, and, the said screen being 45 also inclined, the remainder of such particles will be worked through without other action than that of gravity. Hence the mere act of pouring effects the sifting also, and as it is usual to have a receptacle for the accumulation of ashes, the sifter itself may be 50 made said receptacle, so that every scuttleful thrown in will certainly be sifted, resulting in considerable saving of fuel.

My screen is constructed as seen in the 55 drawing, the box being shaped to conform

somewhat to the direction taken by the ashes as it is being sifted. The bottom is divided by a low partition into two compartments of about equal dimensions, and into which drawers, (a) and (b), are fitted. The sifter or screen, seen at (c), lies in an inclined position over (a), the lower end resting upon the partition and the other near the top of the back end of the box, at which place is a narrow opening (d), (covered by a flap) to 60 admit or remove the screen. At the highest part of the box is an oblong opening extending all across, and at the front edge of this I place an inclined chute-board (e), but standing perpendicular (or nearly so) to 65 the surface of the screen, the termination of which chute is near the said surface and toward its upper end, as shown. The dust is prevented from escaping by a flap (i) hinged at the top back edge of the opening 70 already named, and so that its lower edge will strike or rest against (e), said flap forming a self-acting door, which, being pressed open by the descending ashes, will 75 close the moment the supply ceases. 80

The operation is as follows. The ashes is represented as being thrown into the hopper from a coal-hod, being sent in in a continuous stream. Sliding directly down the chute-board (e) it forces (i) open and is 85 projected with considerable force squarely upon the screen (c), and near its top. A considerable portion of the ashes passes through at once, leaving the cinders free to roll down and fall into their receptacle (b), 90 the remaining ashes being screened out before they arrive at the bottom, and of course fall into (a). The jarring produced by the rolling down of irregular shaped cinders assists the operation, the screening thus being an entirely self operating performance. The scuttle or hod being emptied, the flap (i) closes, and thus the dust produced by the agitation within is prevented from escaping. 95

Having now fully described my improvement I wish to be understood that I do not lay any claim upon the different parts composing my improved apparatus when separately considered but

I claim in my improved coal ash sifter, the 105 specific arrangement herein described, consisting of the inclined screen in such combination with the chute-board, which is also inclined, that the impact of the stream of ashes and cinders shall be perpendicular (or 110

nearly so) to the surface of said screen; and this I claim when said arrangement is incased within a tight box having a flap or door to close automatically so soon as the ashes have been poured in, by which construction the separation of the cinders is effected by the mere operation of pouring, and by which also the dust incident to said

operation, is prevented from escaping, as set forth.

10

In witness whereof I have hereunto subscribed my name.

SAMUEL BOOTH.
